UNITED STATES PATENT OFFICE

EDWARD G. JOHNSON, OF CAPE MAY, NEW JERSEY

PARACHUTE AND AERIAL LIFE BUOY

Application filed September 19, 1928. Serial No. 308,997.

This invention relates to aerial navigation and safety devices, and particularly to an improved parachute and aerial life buoy, the object being to provide a parachute construction which includes a lighter-than-air formation in certain parts so that a smaller spread to the parachute may be secured and a floating structure presented when the device strikes a body of water.

10 Another object of the invention is to provide a combined parachute and aerial buoy, whereby a buoyant body is provided for the parachute using gas, the arrangement being such that the buoyant body partially 15 supports the weight, whereby a comparatively slow descent is secured.

A further object, more specifically, is to provide a parachute and aerial buoy with a canopy formation and a body formation 20 formed with double walls and means for directing lifting gas between the respective walls so as to provide a certain amount of buoyancy to the parachute structure.

In the accompanying drawings,—

25 Figure 1 is a vertical sectional view through a device embodying the invention, the same being illustrated as supporting a figure;

30 Figure 2 is a top plan view of the device shown in Figure 1, the same being on a reduced scale;

Figure 3 is an enlarged detail fragmentary sectional view through Figure 1 approximately on the line 3—3;

35 Figure 4 is a reduced perspective view of the complete parachute shown in flight;

Figure 5 is an enlarged detail fragmentary view partly in section and partly in perspective showing the gas container and 40 associated parts as the lower part of the parachute illustrated in Figures 1 and 4.

Figure 6 is an enlarged detail fragmentary sectional view illustrating the gas release valve shown partly in Figure 5;

45 Figure 7 is an enlarged detail fragmentary sectional view through Figure 2, approximately on the line 7—7, the same illustrating how the gas passes from one part of the device to the other.

50 Referring to the accompanying drawings

by numerals, 1 indicates a canopy or umbrella and 2 a construction which may be termed a body carrying a suitable platform 3 at the bottom secured to the body 2 in any desired manner, as for instance, by being 55 secured to the ring 4 which in turn is secured by stitching or otherwise to the body 2. The body 2 at the upper end merges into the umbrella 1 or is rigidly secured thereto, as shown in Figure 7, a suitable ring 5 being 60 used to hold the parts in proper relative position and spaced apart so that an opening 6 will be presented through which the head of a person may extend when the device is in use. The ring 5 may be cemented, stitched 65 or otherwise held in place and thus presents a stiff, unyielding opening through which the head may be moved as desired. As clearly illustrated in Figure 1, the umbrella 1 is double-walled and the respective walls 70 are connected by suitable bracing strips 7 of fabric of any desired kind. The respective walls of the umbrella 1 may be formed from treated silk or other material which is 75 gas-proof or substantially gas-proof. A 80 number of openings or passageways 8 are provided in the umbrella 1 so as to allow a certain amount of the compressed air within the umbrella to escape and thus permit the entire device to drop gently and without 85 appreciable oscillation. Also, these openings prevent a strain on the parts near the ring 5 caused by the compression of air near body 2. Body 2 is also provided with inner 90 and outer walls connected together at the ends but spaced centrally, whereby a suitable gas chamber is produced connected with the gas chamber produced between the walls of umbrella 1, said connection being by suitable pipes or tubes 9 and 10. On the platform 3 is mounted a container 11 preferably of metal and in this container is preferably provided a lifting gas under considerable pressure. Flexible pipes 12 and 13 extend 95 from container 11 to points between the walls of the body 2, so that when gas is admitted into body 2 some will pass upwardly through the tubes 9 and 10 so that when there is sufficient gas the umbrella will be inflated, as well as the body 2. A suitable 100

valve 14 is provided and normally maintain the pipes 12 and 13 closed, but when the person using the device presses downwardly on the lever 15 valve 14 is opened against the action of spring 16. When the umbrella 1 is spread out, as shown in Figure 1, it will act in the ordinary manner of a parachute and by the inflating of the parts as just described appreciable buoyancy is secured, said buoyancy being increased as more gas is used. Preferably the parts are so proportioned that the lifting action of the gas when all has been used is slightly less than a quantity sufficient to overcome the weight of the parachute and the weight of an average parachutist. When the parachute is first released from the balloon, airplane or other airship only a small part of the gas is used. As the parachute descends, if the parachutist sees that the landing place is probably objectionable more and more gas is admitted until the descent is almost checked, whereby the parachute may drift for a considerable distance and give the parachutist a chance to land at a desirable point. Where the parachute is to land in the water usually all of the gas is used almost immediately and when the parachute strikes the water it will only be partly submerged, and in fact, will be so buoyant as to support not only the parachutist but many times the weight of the parachutist. The umbrella 1 is preferably circular and one continuous structure, while the body 2, as shown in Figure 3, is divided at line 17. The point of division of the body may be connected together by suitable straps and buckles 18, so that a barrel-shaped structure will be produced. This is not intended as a water-tight structure, but merely to hold the parts in a desired position, whereby the device will alight properly on the water or the land. From Figure 1 it will be seen that suitable openings 19 and 20 are provided in the body 2 through which the arms of the parachutist may extend as the parachute drops. In forming the umbrella 1 and the body 2 any suitable form of reinforcing members, as for instance, ropes, may be used without departing from the spirit of the invention and a certain number of guy ropes 21 are used, as shown in Figure 1, to connect the lower part of the body 2 to certain parts of the umbrella 1, whereby the umbrella will remain spread and the parts will function in the proper manner to descend comparatively slowly and at the same time hold the parachutist in a substantially upright position.

What I claim is:-

- 60 1. A combined parachute and aerial life buoy, including a double-walled umbrella having an opening in the center and a plurality of air vents between the center and the periphery, a double-walled barrel shaped body connected to the center of the

umbrella near the center opening, means acting as a platform connected to the bottom of said barrel-shaped body for supporting a person within said body means carried by said platform for discharging lifting gas into the body and the umbrella, and guy members for connecting the outer portion of the umbrella with the bottom of the body. 70

2. A parachute, including a gas filled umbrella, means connected with the umbrella for supporting a person said means including a platform positioned substantially at the lowest point on the parachute, a gas tank carried by said platform, means for connecting the gas tank to the gas filled umbrella, and a foot operated valve positioned adjacent the feet of a person standing on said platform for controlling the flow of gas from the tank to the gas filled umbrella during the descent 80 of the parachute. 85

3. A parachute, including a double-walled gas-filled umbrella formed with a central opening through which the head of the parachutist may extend, a double-walled gas filled body connected to the center of the umbrella, said body being shaped so that the inner walls thereof will be spaced from the person carried by the parachute, said body also having openings adjacent the under 90 surface of said umbrella through which the arms of the person carried by the device may extend, and means carried by the bottom of the body for supporting a person. 95
